UNITED STATES PATENT OFFICE

141,169

DESIGN FOR A COMBINED HAIR STAY AND FASTENING MEANS

Mario Petitta, New York, N.Y.

Application February 20, 1945, Serial No. 118,062

Term of patent 3½ years

(Cl. D86—10)

To all whom it may concern:

Be it known that I, Mario Petitta, a subject of Italy, residing in New York city, county of New York, and State of New York, have invented a new, original, and ornamental Design for a Combined Hair Stay and Fastening Means, of which the following is a specification, reference being had to the accompanying drawing, forming part thereof, wherein,

Figure 1 is a front elevational view of a com-

bined hair stay and fastening means showing my new design.

Figure 2 is a side elevational view, and

Figure 3 is a rear perspective view of the combined hair stay and fastening means shown in Figures 1 and 2.

I claim:

The ornamental design for a combined hair stay and fastening means, substantially as shown.

MARIO PETITTA.
